UNITED STATES PATENT OFFICE.

VITUS SCHWANINGER, OF OGGERSHHEIM, GERMANY.

APPARATUS FOR RAISING LIQUIDS.

SPECIFICATION forming part of Letters Patent No. 726,359, dated April 28, 1903.

Application filed October 30, 1901. Serial No. 80,579. (No model.)

To all whom it may concern:

Be it known that I, VITUS SCHWANINGER, a subject of the King of Bavaria, residing and having my post-office address at Oggersheim, 5 in the Palatinate, Germany, have invented certain new and useful Improvements in or Relating to Apparatus for Raising Liquids, of which the following is a specification.

The present invention relates to an apparatus for raising liquids, especially acids, in which when a vessel or chamber has been filled with the liquid to be raised the device shutting off the pressure agent (steam, compressed air, or the like) is opened by means 15 of a float, by which the said device is closed again toward the end of the period of pressure.

The annexed drawing represents a vertical section of the apparatus.

20 The pressure-chamber 1 is connected by the pipe 2, controlled by the antireturn-valve 3, with the supply-pipe 4 of the liquid to be raised and by the valve 5 with the conduit 6 of the pressure agent. The air-discharge valve 25 7 connects the interior of the pressure-chamber 1 with the outer atmosphere. The pipe 2 is connected near the valve 3 with the pipe 8, which leads to the tank 9. The float controlling the valve 5, which shuts off the pressure agent, consists of two parts 10 and 11, 30 rigidly connected with each other. As will be shown, it is this special construction of the closed hollow float which produces the automatic opening and closing of the valve 5 at the beginning and toward the end, respectively, of the period of pressure, so that the 35 said float forms the principal feature of the present invention.

When a certain degree of overpressure exists 40 in the pressure-chamber 1, the exhaust-valve 7 is forced thereby against its upper seat 12 and shuts off the interior of the chamber from the outer atmosphere. After the period of pressure when the overpressure 45 has passed out through the pipes 2 and 8 the valve 7 falls back again onto its support 13, and thus reopens communication between the interior of the pressure-chamber and the outer atmosphere, so that the air can pass out 50 of the former when liquid enters.

For the purpose of the following description the weight of the entire float 10 11 will

be assumed to be, say, twenty kilograms and the pressure above the valve 5 equal to, say, ten kilograms, so that the total load on the 55 said valve will be thirty kilograms. Assuming, further, that the lower part 10 and the upper part 11 of the float each displace twenty-five kilograms of the liquid to be raised, then when the liquid entering through 60 pipe 4, valve 3, and pipe 2 has entirely covered part 10 of the float the valve 5 will be held closed by a load of thirty minus twenty-five equals five kilograms. The liquid continues to rise, the air contained in the pressure-chamber escaping past the exhaust-valve 7 until the upper part 11 of the float is 65 so far immersed in the liquid that the remaining load of five kilograms holding down the valve 5 is also overcome and the latter is 70 opened. The pressure agent in the conduit 6 now enters the pressure-chamber, closes the exhaust-valve 7, and forces the liquid up through pipe 2 and valve 3 into the conduit 8. The pressure of ten kilograms above the valve 75 5 being now counterbalanced, the lower part of the float holds the said valve open during the period of pressure with a pressure of twenty-five minus twenty equals five kilograms until the liquid-level has fallen to the 80 position shown in the drawing—that is to say, to the said lower part. The liquid-level will then have reached the lower end of the pipe 2, so that the pressure in the pressure-chamber will equalize itself to that of the outer 85 atmosphere through the pipes 2 and 8, the exhaust-valve 7 will open, and the process described will begin over again.

If it is desired to utilize the expansion of the pressure agent, the shutting off of the 90 latter—that is to say, the closing of valve 5—must take place before the level of the liquid has fallen to the lower end of pipe 2. For this purpose it is sufficient to place the lower part 10 of the float at a relatively higher position—for instance, by loosening the set-screws 15 and 16 and moving the part 10 upward on the rod 14. The expansion of the pressure agent will then take place between the closing of valve 5, which takes place 95 sooner than before, and the moment at which the liquid-level reaches the lower end of pipe 2. It may also in some cases be of advantage to make the upper part of the float ver-

tically adjustable by providing it with set-screws 17 18, as shown in the annexed drawing. It is thus rendered possible to exactly limit or control the quantity of liquid to be raised during each operation of the apparatus.

I declare that what I claim is—

In apparatus for raising liquids the combination of a chamber, means for supplying a pressure agent thereto, a valve for controlling said supply, an air - discharge valve, means for filling said chamber with liquid and a closed float in said chamber, for coöperation with the pressure-supply valve, said 15 float consisting of a lower hollow body, the buoyancy of said lower hollow body when immersed being greater than its own weight, insufficient to raise the said valve against the

pressure agent, but sufficient to hold it when raised, and an upper hollow body, the buoyancy of said upper hollow body when immersed being greater than its own weight and adapted to reinforce the lower part to open the said valve against the pressure agent, the float comprising a rod attached to said pressure-agent-controlling valve, two closed hollow bodies adapted to slide on said rod before starting the apparatus and set-screws for securing the float-bodies to said rod, substantially as set forth.

In witness whereof I have signed this specification in the presence of two witnesses.

VITUS SCHWANINGER.
